UNITED STATES PATENT OFFICE

MARVIN R. KENDALL, OF CHICAGO, ILLINOIS, ASSIGNOR, BY MESNE ASSIGNMENTS, TO
ST. REGIS PAPER COMPANY, OF NEW YORK, N. Y., A CORPORATION OF NEW YORK

BAG

Application filed April 28, 1928. Serial No. 273,490.

This invention relates to a gusseted bag and more particularly to a gusseted bag having its end closed by a seam and folded or creased so as to open out in the desired manner. Details of the invention will appear as the description proceeds.

In the accompanying drawings, Figure 1 is a view of one end of a bag, with parts broken away, before the end of the bag is creased; Figs. 2 and 3 are views looking, respectively, at the left and right sides of Fig. 1; Fig. 4 is a view similar to Fig. 1, but showing the bag after the opening out or creasing operation has commenced; Figs. 5 and 6 are views, respectively, of the left and right sides of Fig. 4; Fig. 7 is a view of the right side of the end of a bag as shown in Fig. 4, but after the creasing operation is completed; Figs. 8 and 9 are views, respectively, of the left and right sides of the end of the bag after the creasing operation is completed; Fig. 10 is a plan view of the end of the bag creased as shown in Figs. 7, 8 and 9; Fig. 11 is a view similar to Fig. 9, but taken after the end of the bag is turned to bring it parallel with the body of the bag; Fig. 12 is a view of the valve end of the bag illustrating how the bag may be picked up to put it on a filling device; Fig. 13 is a perspective view of the right end of the bag when it is picked up for placing it upon the filling apparatus; Fig. 14 is a side view of a bag in filling position; Fig. 15 is a view of the bottom of the bag partially opened; Fig. 16 is a view of the bottom of the filled bag; Fig. 17 is a view of the developed blank, indicating the lines on which it is folded; and Fig. 18 is a section of the end of the bag on the central vertical plane of Figs. 5 and 6.

It is old to form a gusset folded bag formed with a tubular body portion 20 and having a gusset 21 extending completely along one side and having a gusset 22 extending from one end to nearly the other end of the other side, there being a valve 23 folded in at one end of gusset 22. The end of the bag is shown as being closed by a reinforcing seam 24. Some difficulty has been encountered in placing such a bag upon the tube of a filling machine adapted to fill

valve bags. In order to avoid this difficulty, I open up and crease the end of the bag in the manner described below. When the gussets 21 and 22 are opened up adjacent the seam and the seam is pressed towards the body of the bag, the sides spread along lines 25 and 26. At the valved corner of the bag this merely results in opening up the valve in the manner indicated in Fig. 5. At the other corner of the bag, there being no valve, the gusset is partially straightened along line 27 connecting the ends of lines 25 and 26. From this point the paper slants inward at the top to point 28 where the upper end of gusset 21 is caught in seam 24 and downward to point 29 where the gusset may be held together.

When the movement is continued until the gussets are completely spread, the valve is once more collapsed, as shown in Fig. 8, and the gusset is completely straightened along 70 27 and the sides of the walls are brought against the walls folded along line 27, as shown in Fig. 9. After the bag has been thus creased along lines 25 and 26, the bag may 75 be straightened out once more to the position in which it is shown in Fig. 1, for purposes of transportation, but preferably the end of the bag is tipped over, as shown in Fig. 11, so that it lies substantially parallel with the 80 body of the bag.

When the bag has been creased and folded in the manner described, it may be picked up by the seam, as indicated in Fig. 12, whereupon the bag automatically returns to the position in which it is shown in Figs. 4, 5 and 6 and in perspective in Fig. 13. When in this position, the valve is opened up, as shown in Fig. 5, and may be readily slipped over the end of a filling tube 30, as shown in Fig. 14. 90

The bottom of the bag may be made in the same way as the top of the bag, except that there is no valve. If this is done the bottom of the bag is closed by a seam 31 and the bag is creased along lines 32 and 33, the gusset being straightened along line 34, lines 32, 33 and 34 corresponding as to lines 25, 26 and 27, respectively, of Fig. 6, except that they are formed at the bottom of the bag. It will be readily understood that the bottom of the 100

bag is the same at both sides thereof. When the bottom of the bag is creased in this manner, it automatically opens up in the manner indicated in Fig. 15 as soon as the bag begins 5 to open, the paper along lines 34 acting substantially as a brace to keep lines 32 and 33 spread apart. Seam 31 may fall away from line 34, slightly, at the start, but when the material enters the bag it promptly spreads 10 apart lines 32 and 33, spreading the bag along line 34, as shown in Fig. 16.

It will be readily seen from the above that my method of creasing the end of the bag is advantageous at the valved end of the bag 15 because it enables the operator to place the bag on the filling tube with one hand, since the outstanding seam is readily seized and the valve opening opens up automatically when the bag is lifted by the seam. Furthermore, 20 it provides for the proper opening and filling of the bottom of the bag.

In the construction shown the creases along lines 25, 26, 32 and 33 are at a distance from the respective end-closing seam substantially 25 equal to the depth of the gusset fold, and this is the preferred arrangement, but the end might be spread more or less than the width of the gusset if desired. In the construction shown the creases 25 and 26 reach the valve 30 opening at the middle of the sides of the valve, and that is the most advantageous position for readily opening the valve, but a similar advantage is obtained by a crease anywhere in the middle portion of the sides of the 35 valve.

Other changes may be made in the construction of the bag and in the manner of creasing, within the terms of the appended 40 claims.

40 What I claim is:

1. A bag comprising a tubular body portion having gusset folded sides and an outstanding end closing seam, the walls of the bag being creased across the end substantially 45 parallel with the seam and at a distance from the seam substantially equal to the depth of the gusset fold.

2. A bag comprising a tubular body portion having gusset folded sides and an outstanding end closing seam, the gusset folds being collapsed except adjacent the seam where the gusset is straightened, this straightened portion of the gusset being bent 50 into alignment with the body portion of the bag.

3. A collapsed bag having an end closed by an outstanding seam, one corner being tucked in adjacent the seam to form a valve and the valve being spread laterally of the bag and 55 then bent into alignment with the body of the bag.

4. A valve bag comprising a body portion closed by an outstanding seam and having its wall tucked in adjacent one end of the seam to form a valve, the wall being creased

substantially parallel with the seam along lines midway of the sides of the valve opening.

5. A valve bag having one end closed by an outstanding seam and a valve opening 70 adjacent one end of the seam, the walls of the bag being creased along lines running away from the midway portion of each side of the valve.

In testimony whereof, I have hereunto 75 signed my name to this specification.

MARVIN R. KENDALL.
